UNITED STATES PATENT OFFICE.

OLIVER J. LODGE, OF LIVERPOOL, COUNTY OF LANCASTER, ENGLAND.

LIGHTNING-ARRESTER.

SPECIFICATION forming part of Letters Patent No. 429,727, dated June 10, 1890.

Application filed May 22 1889. Serial No. 311,676. (No model.)

To all whom it may concern:

Be it known that I, OLIVER JOSEPH LODGE, D. Sc., F. R. S., a subject of the Queen of Great Britain, residing at Liverpool, in the county 5 of Lancaster, in the Kingdom of Great Britain, have invented certain new and useful Improvements in Lightning-Protectors, of which the following is a specification.

As the result of a long course of experiments on the conditions and phenomena of high-tension discharges, I have arrived at a method of reliably protecting any kind of apparatus from the effects of lightning or any other high-tension currents, however generated, which are not intended to enter it.

In the apparatus at present in use a short lead is brought from the line-wire to an air-gap electrically connected on the other side with the earth, the resistance of this course 20 being intended to be made so much less for high-tension electricity than the path through the instruments that the greater part of the high-tensional charge shall be shunted to earth.

By the term "air-gap" I mean any insulating-space arranged as a shunt to the thing to be protected—*i. e.*, any arrangement such as is already employed as a lightning-arrester, or such as might easily be employed. The 25 shape of the opposing surfaces is immaterial, and the nature of the insulating substance between them is likewise optional. Thus by the term "air-gap" I intend to include a pair of knobs close together, or the space between the rounded ends of two rods, or between two plates, or between two points, or between a wire and a tube surrounding it, or any such already well-known plan. Similarly the insulating substance in the gap may be air, or it 30 may be a thin film of mica or other solid insulator, as in the protectors used in the British Land Telegraph, as set forth in Figure 5, or it may be a partial vacuum, as in Varley's protectors. (Shown in Fig. 8.) In the instrument 35 most used by cable companies the air-gap is the space between a central thin wire and a point-carrying tube surrounding it, as set forth in Fig. 6. In telephone-protectors it is the space between the teeth of two 40 combs, as set forth in Fig. 7. In Varley's it is the space between two wires in a vacuum-tube, as set forth in Fig. 8, and so on. I in-

clude under the word "air-gap" any of these already well-known lightning-protecting devices.

My invention relates to the mode of connecting them "up."

My invention consists in the use of a number of such air-gaps connected to each other by coils of wire or ribbon, which oppose the current rather by self-induction or electro-magnetic inertia than by resistance proper. The line-current has to go past all of the air-gaps, while the momentary high-tensional currents are shunted through the gaps. The gaps are of either adjustable or fixed width, and the line-current has to go past all of the air-gaps, while the momentary high-tensional currents are shunted through the gaps. The apparatus to be protected, 70 whether it be lamps, or inside wires, or underground or submarine cables, telephones, telegraphic instruments, galvanometers, meters, or any other kind of electrical apparatus, is connected to the last air-gap of the series. 75 The line-wire, or exposed leads, or other wires into which it is feared that lightning or high-tension currents may possibly come, are connected to the first air-gap of the series.

Referring to the drawings, Fig. 1 shows a simple form of carrying my invention into effect with adjustable air-gaps; Fig. 2, a simple arrangement for lightning-switch, specially useful at the junction of overhead and underground or submarine lines, or other position 85 where there are covered wires or cables to protect; Fig. 3, an arrangement useful at an intermediate telegraph-station having no earth-connection. Fig. 4 shows the invention utilizing existing lightning-protectors, such as plates or tubular protectors. Figs. 5, 6, 7, and 8 are detail views of well-known devices for shunting currents of more than desired strength.

Like letters refer to like parts in all the drawings.

Referring first to Fig. 1, A and B are the terminals inserted in the leads, or A is connected with the line-wire and B with earth. C D are terminals connected with the instrument to be protected, or C with the instrument and D with the earth, or C with the instrument and D left insulated, as desired.

E' E², &c., represent air-gaps.

G' G³, &c., are self-induction coils, consisting, for instance, of gutta-percha-covered wire coiled upon bobbins.

The action of the arrangement is as follows: The ordinary currents which it is intended to transmit through the apparatus to be protected traverse the self-induction coils G' G³, &c., and do not jump any of the air-gaps; but lightning or any other foreign and violent currents which may accidentally have got into the leads will jump one or more of the series of air-gaps, and be thus diverted from the instruments or lamps to be protected. Thus the insulating-spaces or air-gaps may be arranged so that the greater portion of a violent discharge will jump the first E'; a certain fraction—say a tenth—of the remainder will jump the second E²; another fraction—say a tenth of this again—will jump the third E³, and so on, the amount finally permitted to go through the protected instrument being thus reduced to any desired amount.

It may be well to set the air-gaps or insulating-spaces of different widths—for instance, the first having broad rounded ends wider apart than the second, exposing larger surface and capable of easy examination and replacement, as by binding-screw h, in case of damage by a flash; the second small rounded ends or points close together and capable of minute adjustment by screwing up, as shown, with lock-nuts or equivalent device; the third still closer and finer, &c. It may also be well to vary the connecting-coils, using thicker and more highly-insulated wire for the earlier coils and thinner for the later, as shown.

Fig. 2 shows a variation useful for protecting the insulation of covered wires or cables in which the exposed line is attached to terminal A and the protected one to C. B is connected to earth.

The first F' is preferably a knob, plate, or rounded end, as shown, and of stout conducting material. The second and subsequent ones F³ F⁵, &c., can be knobs or points, preferably the latter, and can be adjusted nearer the central knob F² than F' is.

In place of self-induction coils I may use straight wires, carbon rods, mercury-tubes, or other conducting arrangement giving sufficient impedance or resistance, can be used; also each of the knobs or points F² F⁴ F⁶ F⁸ can be connected directly with the earth instead of with each other.

In Fig. 3, A is connected to the up-line wire, B to the down-line wire, C and D to all the instruments in the station, and K to the earth. The conductor K, connected with the earth, is placed between the entrance and exit wires, each of which is provided, (with a series of knobs, plates, or points with self-induction coils between,) forming air-gaps with this conductor.

I am aware that it has been proposed here-

tofore to protect a dynamo-machine or other instrument from abnormally-high-tension currents by placing a self-induction coil on the main-line circuit between the safety-branch or broken ground-connection and the machine to be protected, and I do not broadly claim this as my invention.

I claim as my invention—

1. As a lightning-protector, a series of two or more air-gaps arranged one after the other on the line-circuit with self-induction coils between, whereby the greater portion of the high-tension electricity is shunted at the first gap, the greater portion of the remainder at the second, and so on. 80

2. A series of two or more knobs or their equivalents, each independently electrically connected with the line-wire or lead, but having self-induction coils between them in the line-wire, and one or more conducting-surfaces in communication with the earth placed in juxtaposition, but not actually touching the first-mentioned set, substantially as and for the purposes described. 85

3. The combination of a series of insulating-spaces or air-gaps with self-induction coils between, of a series of independent adjustable devices, whereby the width of gap can be regulated. 90

4. In a protector against lightning or high-tension electricity formed of a series of air-gaps, as described, with self-induction coils between, a first gap of very stout proportions and discharging capacity, and succeeding ones of smaller proportions and capacity, whereby each part is proportioned to the work it has to do. 95

5. In a lightning or high-tension-current protector, a series of air-gaps with self-induction coils between them, said gaps being successively narrower, substantially as described. 105

6. In a protector against lightning or high-tension electricity formed of a series of air-gaps with self-induction coils between, the arrangement of a first gap with large opposing surfaces, and the latter gaps with smaller opposing surfaces, whereby the bulk of the high-tension electricity can pass with less injury to the apparatus and the residue with more ease owing to the conductors being pointed. 110

7. The combination, with existing protecting devices, of one or more additional air-gaps with self-induction coils between each of said lightning-protecting devices or air-gaps and the next, whereby the residual high-tension electricity that would pass the existing lightning-protecting devices is eliminated, substantially as described. 120

In testimony whereof I have signed my name to this specification in the presence of two subscribing witnesses. 125
